UNITED STATES PATENT OFFICE.

GEORGE D. LEADBETTER, OF DETROIT, MICHIGAN.

PERAMBULATOR.

SPECIFICATION forming part of Letters Patent No. 728,253, dated May 19, 1903.

Application filed October 21, 1902. Serial No. 128,155. (No model.)

To all whom it may concern:

Be it known that I, GEORGE D. LEADBETTER, a citizen of the United States, residing at Detroit, in the county of Wayne and State of Michigan, have invented certain new and useful Improvements in Perambulators, of which the following is a specification, reference being had therein to the accompanying drawings.

10 The invention has particular reference to folding perambulators; and it consists in the novel construction of the device and the peculiar arrangement and combination of the various parts thereof, as will be more fully 15 hereinafter set forth, and pointed out in the claims.

In the drawings illustrating my invention, Figure 1 is a perspective view of the perambulator. Fig. 2 is a view in elevation showing the perambulator in its folded position. Fig. 3 is a detail view illustrating the adjusting mechanism for the back frame.

The reference-letter A designates the handle-frame of the perambulator, provided with 25 a forwardly-extending section B, which carries the front wheels C. Pivoted intermediate of its ends to the handle-frame is the complementary frame D. This frame projects rearwardly of the handle-frame and 30 carries the rear wheels E.

F designates bearings in the form of apertured ears secured to the handle-frame A and projecting forwardly therefrom. Pivoted within these bearings is the seat G, carrying 35 studs a, which engage the apertures in the ears.

H represents brackets, one upon each side of the seat in proximity to its rear edge. Each bracket has a slot I formed therein, extending 40 rearwardly in a substantially horizontal direction and then upwardly at an angle thereto.

J represents studs carried upon the forward free ends of the complementary frame D, which engage the slots in the brackets. The brackets and the forward portion of the complementary frame are so arranged and proportioned that upon the folding of the seat the studs J will travel within the slots and 45 the two frames will be drawn into a folded position. When folded, the seat, being journaled in advance of the handle-frame, will

be spaced from said handle-frame a slight distance, the space being sufficient to receive the cushion ordinarily carried on the seat. 55 Means are thus provided for permitting the seat to be folded compactly against the handle-frame to occupy a minimum amount of space with the cushion thereon.

K designates a rear frame or back which has a pivotal connection at its lower end with the handle-frame. The preferable connection I have shown as consisting of a rod c, extending transversely of the handle-frame and passing through the lower end portions 65 of the back. A similar rod d is preferably secured to the rear side of the back frame and projects a slight distance beyond the opposite sides thereof, forming studs or journals d. Racks L are provided for the handle-frame, one upon each side thereof, with which the studs or journals d are adapted to engage and permit of the back being moved and locked into different positions of adjustment relative to the handle-frame. 75

M represents the arm-rests of the perambulator, each pivoted to the back frame K, being preferably connected to the studs d, and O is a folding foot-rest which has connections with the seat and with the arm-rests. 80 Preferably these connections comprise a pair of connecting members in the form of rods e and f, one pair being arranged upon each side of the seat, and the ends of each pair being pivoted respectively to the arm-rest M and 85 to the foot-rest O. One or more of these connecting members may be secured to the seat G. The preferable construction is as shown, wherein the members e of each pair are pivoted to the seat, as at f'. 90

It will be obvious from the construction of the perambulator that the seat upon being folded into parallelism with the back frame not only causes the two complementary frames to be drawn together, but also moves 95 the arm-rests and the foot-rest into planes parallel with the handle-section, the parallel connecting members described acting to turn the foot-rest so that it will assume a vertical position. It will be further noticed that as 100 the back frame is adjusted either rearwardly or forwardly relative to the handle-frame the foot-rest is correspondingly adjusted, but in an opposite direction, so that it will be in a

proper inclined position relative to the back for the occupant when either in an upright or inclined position.

What I claim as my invention is—

- 5 1. In a perambulator, the combination with the wheeled handle-frame having forwardly-extending bearings, of the seat, supplemental bearings secured to the seat and pivoted at their rear edges to the forwardly-extending 10 bearings, said supplemental bearings having slots therein, and a complementary wheeled frame pivoted to the handle-frame and having studs for engagement with the slots in the supplemental bearings.
- 15 2. In a perambulator, the combination with the wheeled handle-frame having forwardly-extending bearings, of the seat, supplemental

bearings secured to the seat and pivoted at their rear edges to the forwardly-extending bearings, said supplemental bearings having 20 slots therein, one portion of said slots occupying a plane parallel with the plane of the seat and the other portion extending at right angles to and adjacent the rear edge of said seat, and a complementary wheeled frame 25 pivoted to the handle-frame and having studs for engagement with the slots in the supplemental bearings.

In testimony whereof I affix my signature in presence of two witnesses.

GEORGE D. LEADBETTER.
